UNITED STATES PATENT OFFICE.

CHARLES HAMANN, OF BROOKLYN, NEW YORK.

BOTTLE-WASHER.

1,241,508.

Specification of Letters Patent.

Patented Oct. 2, 1917.

Application filed August 27, 1913. Serial No. 786,905.

To all whom it may concern:

Be it known that I, CHARLES HAMANN, a citizen of the United States, residing at New York city, borough of Brooklyn, county of 5 Kings, State of New York, have invented certain new and useful Improvements in Bottle-Washers, the following being a full, clear, and exact disclosure of the one form of my invention which I at present deem preferable.

For a detailed description of the present form of my invention, reference may be had to the following specification and accompanying drawings forming a part thereof, in 15 which—

Figure 1 is a plan of my apparatus;

Figs. 2 and 3 are detail views in elevation showing the manner of supporting the bottles;

20 Fig. 4 is a side elevation partly in section and

Figs. 5 and 6 show details on an enlarged scale.

My invention relates to certain improvements 25 on the bottle-washer of my Patent No. 1,068,648 of July 29th, 1913, which improvements will be recited in detail.

In the drawings, L represents a vertically disposed main carrier shaft operated by a 30 horizontal drive shaft A which in this case is applied to the upper end of the vertical shaft L, this being an important improvement over my former machine, wherein it was applied to the lower end thereof. Rotatably mounted on shaft L, is a horizontal table or carrier C on which the bottles are placed, said carrier being rotated by means 35 of gears 1 and 4, attached to the shaft and table respectively, and the intermediate pins 40 ions 2 and 3. On this table C are the usual pins P for receiving the bottle, each having a rubber fin for scouring the interior of the bottle as it rotates. I also add, by my present invention, a series of vertical guard rods 45 P¹ on the table alternating with pins P and having, each of them, a rubber faced roller P² at its upper end; these are shown in Figs. 2 and 3. On that part of the table where the bottles are not in contact with the scrubbing 50 belt the bottles will stand vertically and out of contact with rollers P² so that the rollers will not interfere with the quick application of the unwashed bottles to the pins P and the removal of the washed bottles therefrom.

55 When, however, the bottles come in contact

with the scrubbing belt, the drag thereof causes the bottles to rotate and to tilt rearwardly as shown in Fig. 3 when they will bear upon the rollers, which will limit the degree of tilting and also permit the free 60 rotation of the bottle on pin P. By this expedient, in connection with the further improvements I will describe hereafter, I am able to handle quart bottles on my machine which was previously limited to the 65 washing of pint bottles.

My improved scrubbing belt is shown in detail in Figs. 5 and 6. On each of the vertical posts R and R¹ is journaled a double sprocket wheel. The one on post R is lettered D, D and comprises an upper wheel D and a similar lower wheel D, the two being secured together by vertical rods d¹ carried on the extremities of the several spokes d² which radiate from the hub d³. A similar 70 double sprocket wheel is journaled on post R¹ and the upper wheel thereof (shown in Fig. 5) is marked D¹. On the two upper wheels D and D¹ runs a sprocket chain while a second sprocket chain runs on the two 75 lower wheels D and D¹. The alternate links g, g, etc., of the upper chain are each cross-connected with the corresponding link g of the lower chain by a vertical strip x, each strip being slightly curved as appears in the 80 plan view of Fig. 5. To each strip x is secured, parallel therewith, the back of a separate scrubbing brush G. By this means I provide a flexible belt composed of a series 85 of rigid brushes, or brush sections, which are 90 jointed together through the links of the sprocket chains. On the vertical post R² are fixed two brackets S and S¹, one above the other, and spaced apart a distance about equal to the width of the scrubbing-belt. 95 Each of these brackets carries a curved carrier-plate S² which follows an arc concentric with the table which carries the bottles. On top and bottom of each curved carrier-plate S² is a series of rollers, those on the upper 100 plate being marked k and those on the lower plate k¹. The rollers on top of each plate alternate in position with those on the bottom of the same plate and each set forms an arc shaped roller guide on which the scrubber-belt may travel in a route concentric with the route followed by the bottles on the rotating table or carrier.

The bottles are held in contact with the scrubbing-brush belt by means of two over- 105

110

lapping flat belts f and f^1 just as in the machine of my former patent aforesaid, the belt f being carried by the pulleys H and F^1 while the belt f^1 is carried by the pulleys 5 H^1 and F . These pulleys are driven by the sprocket chain b , as in my former machine, which chain also drives the brush-belt as formerly, but in the present machine the vertical shaft L (whereon is the sprocket 10 wheel m that drives the said chain b), is located concentrically with the table C , instead of being outside of the carrier as in my former machine.

In Fig. 4 there also appears the usual 15 bottom-brush G^2 and the neck-brush G^3 which form no part of my present invention.

What I claim as new and desire to secure by Letters Patent is:

1. An improved bottle washer comprising 20 a main carrier shaft, means for rotating the same, a bottle carrier rotatably mounted upon said shaft, means operated by said shaft for rotating said carrier, a brush belt having a portion traveling in a route parallel with the route of the bottles on said carrier, and means operated by said carrier shaft for actuating said brush belt.

2. An improved bottle washer comprising 30 a main carrier shaft, means for rotating the same, a bottle carrier rotatably mounted upon said carrier shaft, means operated by said carrier shaft for rotating said carrier, and means also operated by said main carrier shaft for cleaning the exteriors of 35 bottles on said carrier.

3. An improved bottle washer comprising 40 a main carrier shaft, means for rotating the same, a bottle carrier rotatably mounted upon said carrier shaft, means operated by said carrier shaft for rotating said carrier, means also operated by said main carrier shaft for cleaning the exteriors of bottles

on said carrier, and means also operated by the carrier shaft for rotating the bottles.

4. An improved bottle washer comprising 45 a main carrier shaft, means for rotating the same, a bottle carrier rotatably mounted upon said carrier shaft, means operated by said carrier shaft for rotating said carrier, a brush belt having a portion traveling in 50 a route parallel with the route of the bottles on said carrier, means operated by said carrier shaft for actuating said brush belt, and means also operated by the main carrier shaft for rotating the bottles.

5. An improved bottle washer comprising 55 a main carrier shaft, means for rotating the same, a bottle carrier rotatable upon said carrier shaft, spaced apart posts rotatably supported above said bottle carrier, double sprocket wheels attached to the respective posts, sprocket chains connecting the sprocket wheels of the respective posts, brush sections attached to said chains, and means operated by said main carrier shaft 60 for rotating one of said posts.

6. An improved bottle washer comprising 65 a main carrier shaft, means for rotating the same, a bottle carrier rotatably mounted upon said carrier shaft, means operated by said shaft for rotating said carrier, internal bottle supports mounted upon said carrier, means operated by the main carrier shaft 70 for rotating said bottles, and external supports for the bottles alternating with said internal supports.

In witness whereof I have hereunto set my hand, before two subscribing witnesses, this 26th day of August, 1913.

CHARLES HAMANN.
